UNITED STATES PATENT OFFICE.

ELIZABETH IDA FLETCHER, OF NORWICH, CONNECTICUT.

ROLLING-PIN.

1,212,039.

Specification of Letters Patent. Patented Jan. 9, 1917.

Application filed March 13, 1916. Serial No. 83,853.

To all whom it may concern:

Be it known that I, ELIZABETH IDA FLETCHER, a citizen of the United States, residing at Norwich, in the county of New 5 London and State of Connecticut, have invented certain useful Improvements in Rolling-Pins, of which the following is a specification, reference being had therein to the accompanying drawing.

10 This invention relates to improvements in rolling pins, one object of the invention being the provision of a sanitary rolling pin in which the dough contacting surface is removable, and is preferably composed of 15 removable sheets of impervious flexible material, as paraffined paper.

A further object of the present invention 20 is the provision of a rolling pin in which the removable sheets of impervious material are so arranged as to be readily torn off to present a new clean sheet or surface to the pin.

A still further object of the invention is the provision of a rolling pin which is simple and inexpensive, as well as sanitary, 25 thus producing a thoroughly efficient and practical rolling pin for the housewife and cook.

In the accompanying drawings:—Figure 1 is a perspective view of a complete pin, 30 and Fig. 2 is a longitudinal section thereof. Fig. 3 is a fragmentary vertical longitudinal sectional view showing a slight modification.

Referring to the drawings, the numeral 5 designates the body of the pin, which is 35 preferably hollow, and made of some light stiff material, as for instance "bristol" board, or even sheet metal, the handles 6, being provided and carrying the pin engaging rim 7, which fits upon the end of the pin, 40 and provides a clamp to hold the spiral or concentric roll 8 of paper about the roll, and so that the sheets may be easily torn off.

Where a concentric roll is employed, each sheet of paper is approximately the circumference of the body 5, and perforated as at 45 9, so that when used or soiled it may be readily torn off. Should the roll be spirally wound upon the body of the pin, each sheet is slightly larger than the circumference of 50 the body of the pin, and is provided with perforations to permit of the removal of the same. By this construction the roll 8 is easily placed upon the body 5 by inserting the body therein, after one of the handles has been removed. The ends of the roll are 55 then placed in between the body 5 and the rims 7 of the handle and are thus clamped in place.

Where found desirable, the handles may be dispensed with, in which event, a strip 60 10 of adhesive paper or cloth is placed over the ends of the roll 8 and the body 5, as shown in Fig. 3 of the drawing, and when the sheets have been entirely removed, the body 5 may be thrown away as useless. In 65 either event a sanitary rolling pin having an impervious removable covering is provided, the paper used for the covering being preferably paraffined.

What I claim, as new, is:—

1. A rolling pin, including a hollow cylinder, a roll of impervious paper perforated to provide a plurality of sheets covering the cylinder, and two handle carried clamps for the ends of the cylinder to hold the roll in 75 place.

2. A sanitary rolling pin comprising a cylindrical body, a removable piece by piece impervious covering for the body, and means for clamping the cover to the body at the 80 ends thereof.

In testimony whereof I affix my signature.

ELIZABETH IDA FLETCHER.
